[57] CLAIM

The ornamental design for a combined bottle and cap, as shown and described.

DESCRIPTION

FIG. 1 is a perspective view of a combined bottle and cap in accordance with a first embodiment of my new design; FIG. 2 is a left side elevational view of the combined bottle and cap of FIG. 1, with the right side elevational view being a mirror image thereof;

FIG. 3 is a top plan view of the combined bottle and cap of FIG. 1;

FIG. 4 is a front elevational view of the combined bottle and cap of FIG. 1, with the rear elevational view being a mirror image thereof;

FIG. 5 is a bottom plan view of the combined bottle and cap of FIG. 1;

FIG. 6 is a perspective view of a combined bottle and cap in accordance with a second embodiment of my new design; FIG. 7 is a left side elevational view of the combined bottle and cap of FIG. 6, with the right side elevational view being a mirror image thereof;

FIG. 8 is a top plan view of the combined bottle and cap of FIG. 6;

FIG. 9 is a front elevational view of the combined bottle and cap of FIG. 6, with the rear elevational view being a mirror image thereof; and,

FIG. 10 is a bottom plan view of the combined bottle and cap of FIG. 6.
